Des. 212,359
Patented Oct. 8, 1968

212,359

AIR TREATING MACHINE

Robert T. Martin, 1708 East 4800 South,
Salt Lake City, Utah 84117

Filed July 10, 1967, Ser. No. 7,740

Term of patent 14 years

(Cl. D23—145)

FIG. 1.

FIG. 2

FIG. 3

FIG. 4

FIG. 5

FIGURE 1 is a perspective view of the air treating machine.

FIGURE 2 is an elevation view of the air treating machine, the side opposite that shown having a flat and unornamented surface.

FIGURE 3 is a top view of the air treating machine.

FIGURE 4 is a left end view of the air treating machine shown in FIGURE 2.

FIGURE 5 is a right end view of the air treating machine shown in FIGURE 2.

I claim:

The ornamental design for an air treating machine, as shown and described.
